UNITED STATES PATENT OFFICE.

CHARLES W. GLIDDEN, OF LYNN, MASSACHUSETTS.

DESIGN FOR A RAND-GUIDE.

SPECIFICATION forming part of Design No. 24,268, dated April 30, 1895.

Application filed December 11, 1894. Serial No. 531,527. Term of patent 14 years.

To all whom it may concern:

Be it known that I, CHARLES W. GLIDDEN, a citizen of the United States, residing at Lynn, county of Essex, State of Massachusetts, have invented a new and original Design for a Rand-Guide for Rotary Trimmers, of which the following is a specification, reference being had to the accompanying drawings, forming part thereof.

10 Figure 1 is an outer side perspective view of a rand-guide, showing my design; and Fig. 2 is a similar inner side view thereof.

15 The leading features of my design in rand guide for rotary trimmers consist in a curved base, a shell-like flaring top rising therefrom, and two ears depending from the base.

20 In the drawings the curved base *a* has a shell-like flaring top *b* rising therefrom, gradually decreasing in thickness from the base to its upper edge, and shown as on the outer periphery of the base.

A wall *c* depending from the base is lengthened at or near the ends of the latter to form two ears *d*, in the curve of the wall, and the wall and ears are shown as on or 25 forming a continuation of the inner periphery of the base *a*. The inner sides *d'* of the ears *d* are substantially at right angles to their faces.

I claim—

30 The design for a rand guide for rotary trimmers, substantially as herein shown and described.

In testimony whereof I have signed my name to this specification in the presence of two subscribing witnesses.

CHARLES W. GLIDDEN.
